CLAIM

The ornamental design for a protective electrical wiring device, as shown and described.

DESCRIPTION

FIG. 1 is a top perspective view of the protective electrical wiring device, showing my new design;

FIG. 2 is a top plan view thereof;

FIG. 3 is a side view thereof; and,

FIG. 4 is an end view.

In the drawings, the broken lines are for the purpose of illustrating environment only and form no part of the claimed design.
